DESIGN FOR A SUIT

Harry Zuckerman, New York, N. Y.

Application December 31, 1939, Serial No. 89,052

Term of patent 3½ years

To all whom it may concern:

Be it known that I, Harry Zuckerman, a citizen of the United States of America, residing in the city of New York, county of New York, and State of New York, have invented a new, original, and ornamental Design for a Suit, of which the following is a specification, reference being had to the accompanying drawing, forming part thereof.

Fig. 1 is a front view of a suit showing my new design.

Fig. 2 is a rear view thereof.

The scarf is an integral part of applicant's garment.

The characteristic feature of my design resides in the combination on the specific jacket portion of the suit disclosed of the specific satin trimmed pockets in association with the specific matching collar and lapels, the trimming on said collar and lapels continuing down the front of the jacket as shown.

I claim:

The ornamental design for a suit, substantially as shown and described.

HARRY ZUCKERMAN.
